UNITED STATES PATENT OFFICE.

FRANK G. MCPHERSON, OF BEAVER FALLS, PENNSYLVANIA.

BOTTLE.

Application filed April 19, 1923. Serial No. 633,115.

To all whom it may concern:

Be it known that FRANK G. MCPHERSON, a citizen of the United States, residing at Beaver Falls, in the county of Beaver and State of Pennsylvania, have invented a new and useful Improvement in Bottles, of which the following is a specification.

This invention relates to bottles.

The object is to provide a bottle especially adapted for containing ketchup, salad dressing or other liquid condiments or preparations, the bottle having a novel construction of mouth whereby the contents may be poured therefrom, if desired, in a relatively small stream, such as usually issues from the small neck bottle in general use; in other words, the object is to construct a wide mouth bottle so that it possesses the advantage of a small mouth bottle, so far as restricted discharge of the contents is concerned.

In carrying out the invention, I provide a bottle having means coacting with the usual closure cap for sealing the contents thereof and having a wide neck communicating with the interior similar to bottles in general use for containing pickles, so that the contents may freely drain or gravitate, when inverted, to the mouth of the bottle, where a wall is provided for reducing or constricting the outlet, said wall being formed to permit the insertion of a spoon, when it is desired to spoon out the contents, and also having means for engaging said spoon, when not in use, and supporting the same with the bowl thereof within the bottle and the handle fully exposed for use.

A full and complete understanding of the invention may be obtained from a consideration of the following detailed description, taken in connection with the accompanying drawing forming a part of this specification, it being understood that while the drawing shows a practical form of the invention, the latter is not to be confined to strict conformity with the showing thereof, but may be changed or modified, so long as such changes or modifications mark no material departure from the salient features of the invention, as specifically pointed out in the appended claims.

In the drawing, in which similar reference characters designate corresponding parts throughout the several figures:

Figure 1 is a perspective view of the improved bottle;

Figure 2 is a vertical sectional view through the same;

Figure 3 is a view similar to Figure 2, but looking at right angles to the same and showing a spoon supported therein;

Figure 4 is a top plan view of the bottle with the spoon in place.

The body 1 of the bottle may be of any desired shape or size, that shown being similar to the ordinary bottle used for containing pickles or like goods, and having a relatively large neck 2 through which the contents of the bottle may be easily passed in filling and readily removed by inverting the bottle at the proper angle.

At the upper or mouth end the neck is provided with an annular bead 3, flush with the upper end thereof, which is adapted to receive the fluted flange 4 of the usual metallic cap 5, which is held thereon by the crimping of said flange in the customary manner. Any other form of closure may, however, be provided.

Across the open end of the neck and slightly spaced from the upper edge of the bead 3, is a horizontal wall 6, molded or blown integrally with the body and neck of the bottle, and thus providing a narrow space between the same and the inner face of the cap or closure 5, so as not to interfere with the ready application and crimping of the latter.

The wall or partition 6 covers substantially one-half of the opening through the neck 2, and has a straight free edge 7, at the center of which there is formed an inwardly-extending, dove-tailed recess 8, or other similarly formed recess having a relatively narrow or restricted entrance opening or throat, as clearly illustrated in Figures 1 and 4 of the drawing, the opening thus formed, as defined between the straight, free edge of the partition or wall 6 and the opposed rounded, inner face of the neck, providing ample space for the introduction of the shank 9 and bowl 10 of an ordinary spoon, for the purpose of removing the contents by the spoonful, as may sometimes be desired in the event the bottle contains salad dressing or other similar goods.

The width of the partition 6 and the resultant extent of the outlet opening depends, of course, on the size of the bottle and the neck thereof, as the said opening must be of sufficient size for the free insertion of an ordinary spoon, thus the larger the bottle

neck, the greater the percentage of closed area and the reverse is true in the case of the smaller size necks as will be readily understood.

- 5 In the event the spoon is used, the latter may be engaged and supported by the wall or partition, while the bowl of the spoon remains within the bottle, as shown in Figure 3, the shank portion of the spoon being introduced at its smallest diameter into the recess 8, which will support the spoon when the same is lowered to allow the larger portion of the handle to rest upon the dove-tailed sides of said recess.
- 10 15 In inserting the spoon, the rounded bottom of the bowl 10 thereof is turned towards the rounded portion of the outlet passage-way formed by the interior wall of the neck 2 when the spoon may freely enter the bottle, 20 be filled with the contents thereof, and withdrawn therefrom without spilling, by slightly tilting the bottle, in a well known manner, and when the spoon is engaged in the recess 8, as shown, it is impossible for 25 the same to fall into the bottle, or become accidentally dislodged and yet may be readily grasped and removed from the seat when desired and replaced therein.

If the bottle contains ketchup or some other liquid which it is the custom to pour from the container, it will be seen that the same will freely flow into the neck of the bottle without clogging, as usually happens when the ordinary small neck bottle is used, 35 the reduced outlet provided by the wall or partition preventing too great or too free a flow of the contents in pouring.

From the foregoing it will be seen that a bottle has been provided having an outlet of 40 restricted internal diameter, which permits of the free insertion of a spoon and the removal of the contents thereby, the spoon being supported in the bottle with the handle exposed for repeated use in taking out the 45 contents from the bottle as desired. It will also be seen that the simplicity of the invention, consisting as it does, of the addition of a novel wall or partition, renders the same capable of being easily and cheaply manufactured during the process of blowing or 50 molding the bottle in the usual manner.

I do not wish to be limited to the integral formation of the wall or partition.

What is claimed is:—

1. A bottle having at its mouth an integral substantially horizontal wall or partition extending partially across the same from one side to restrict the outlet, said partition being arranged transversely of the neck of the bottle and spaced from the other edge of the neck, so as to leave a space for the insertion and support of a spoon in a substantially upright position. 55

2. A bottle having a wall extending across the mouth partially closing the same to prevent too free egress of the contents therethrough, said wall having a centrally disposed recess to receive the shank of a spoon, and being arranged below the plane of the upper edge of said mouth so as to provide 70 for the placing of a cap on said mouth to completely cover the same. 60

3. A bottle having at its mouth an integral wall or partition extending partially across the same to restrict the outlet, and having a central dove-tailed or similar recess provided in the free edge of the partition for the reception of the shank portion 75 of a spoon. 70

4. A bottle having a relatively wide neck, 80 an integrally formed partition located in the neck and adjacent to the mouth thereof, said partition being of a form approximating a semi-circle and joined to the interior of the neck around its curved edge, the other 85 edge being straight and spaced from the opposite wall of the neck to provide an outlet for the contents of the bottle or an inlet for the bowl of a spoon. 80

5. A bottle having a relatively wide neck, 90 an integrally formed partition located in the neck and adjacent to the mouth thereof, said partition being of the form of a portion of a circle and joined to the interior of the neck around its curved edge, the other 95 edge being straight and spaced from the opposite wall of the neck to provide a filling opening an outlet for the contents of the bottle, or an inlet for the bowl of a spoon, 100 said straight edge having an inwardly-extending, dove-tailed or undercut recess for receiving the shank of said spoon to support the same with the bowl thereof within the bottle. 100

In testimony that I claim the foregoing 105 as my own, I have hereto affixed my signature.

FRANK G. McPHERSON.
